UNITED STATES PATENT OFFICE.

CHESTER E. ALBRIGHT, OF PHILADELPHIA, PENNSYLVANIA, ASSIGNOR TO REVERE RUBBER COMPANY, A CORPORATION OF RHODE ISLAND.

TABLE BOLSTER FOR USE IN THE TREATMENT OF SKINS AND HIDES.

Application filed April 26, 1921. Serial No. 464,595.

To all whom it may concern:

Be it known that I, CHESTER E. ALBRIGHT, a citizen of the United States, residing at Philadelphia, county of Philadelphia, and 5 State of Pennsylvania, have invented certain new and useful Improvements in Table Bolsters for Use in the Treatment of Skins and Hides, of which the following is a full, clear, and exact description.

10 This invention relates to table bolsters for use in the treatment of skins and hides and method of making same, and has for its primary object providing a more durable and superior bolster at less cost.

15 Referring to the drawings:—

Fig. 1 is an elevation of the bolster showing a skin indicated in outline mounted thereon;

20 Fig. 2 is an end view of the bolster; and Fig. 3 is a vertical sectional view of the bolster shown in Fig. 1 in process of being molded.

Bolsters of the present general type are largely used in tanneries in connection with 25 various treatments of the skins and hides, as for instance in the "unhairing", "fleshing", "setting out", and "putting out" treatments. While my improved bolster may be employed in any of these treatments 30 with equal success and wherever bolsters of this general type are used, the present description will, however, for the purpose of illustration, be confined more particularly to the unhairing treatment.

35 The table upon which bolsters of this type are used resembles a vertical wooden slab, the bolster being hung or mounted over the top edge with its sides hanging down on either side of the table. Each machine 40 generally comprises a series of these vertical tables secured between endless travelling chains which carry the tables in an endless path to and from the operator who hangs the skins or hides over the respective bol- 45 sters in readiness for the desired treatment and removes them therefrom after treatment. Referring now more particularly to the un- 50 hairing treatment the series of vertical tables are carried consecutively upwards between a pair (or pairs) of rotatable knives some- 55 what resembling the ordinary type of lawn- mower with the exception that the blades have rounding edges to effect a scraping ac- tion rather than a cutting action, and the convolutions run in opposite directions from

the centre outwardly somewhat in herring- bone fashion in order that the skin will be subjected to a scraping action downwardly and outwardly from the centre toward the side edges thereby maintaining the skin un- 60 der tension.

The usual method of bolstering the table was to cover it with a sheet of felt some half inch in thickness and over this place a bull- 65 hide a quarter inch in thickness. This type has been substituted by a bolster formed of rubber. All such bolsters are simply taken from the flat sheet and doubled over the table and then nailed or otherwise fastened along their edges in an attempt to keep 70 them flat and even and to conform them to the table. They have, however, always been open to the serious objection that due to their thickness and stiffness they have bulged outwardly on either side of the table, 75 the bulges appearing promiscuously throughout their areas but principally ad- jacent the line of fold at the top of the table. These bulges have materially interfered 80 with the successful operation of the ma- chines and have materially shortened the life of the bolster. For instance in the un- hairing operation it is desirable that the hairs be entirely and perfectly removed from the skin and that the skin be in no 85 way injured during this operation. The knives are under considerable pressure and the principal object of the bolster is to cushion the skin in order that it may be 90 yieldingly supported against the knives dur- ing the scraping action. The skins are of varying thicknesses and it is important that a plane or smooth surface be presented to the knives and that the inequalities appear at the back of the skin instead of the face, 95 the thicker portions being embedded in the bolster so that the pressure of the knives will be evenly distributed over the sur- face of the skin and the skin thereby sub- jected to a uniform scraping action in order 100 that the hairs may be uniformly removed. Wherever a bulge appears in the bolster a corresponding bulge appears in the skin and it is obvious that a skin having these un- 105 even outer surfaces cannot receive a uniform treatment, the higher spots will be ex- cessively scraped and the skin accord- ingly injured while the lower portions will be inadequately scraped thereby leaving some of the hairs remain- 110

ing. Furthermore, as the skins are irregular in contour and vary materially in size, the bolster is made of sufficient size to support the skin and to leave a large margin of 5 the bolster surrounding the skin uncovered. It is obvious that bulges appearing in the bolster at these uncovered portions will be subjected directly to the scraping action of the knives and the bolster thereby seriously 10 injured by rendering it of unequal thickness, so that the skins will not be evenly supported thereby producing unsatisfactory results in the unhairing or other treatment.

As has been previously stated attempts 15 have been made to replace the felt-bull-hide bolster by one made of rubber. The bolsters are under considerable tension by the downward pulling action of the knives as the table is forced upwardly between them. 20 This tension is so excessive that even where pure rubber has been employed its tensile strength has been insufficient to resist this force and the bolster has often been found to crack and break along the fold at the top. 25 Attempts have been made to correct this by reinforcing the rubber with one or more plies of fabric, but while this affords additional strength it very materially increases the stiffness and produces such excessive 30 bulging that a bolster of this construction has proven impractical.

I have found that these defects in the rubber bolster can be overcome if the bolster be "set" in its folded condition, that is 35 to say, if it be given the permanent shape that it will assume when mounted over the table. This will be in most instances approximately U-shaped with the two sides spaced apart to an amount approximately 40 equal to that of the thickness of the table and the portion connecting the two sides being preferably rounded to snugly fit the correspondingly rounded top edge of the table. This will permit the bolster to hang 45 at both sides of the table perfectly flat and comparatively limp or dead requiring no fastenings and presenting no bulges. Such a bolster is represented in the drawing by the numeral 1, Fig. 1, showing a skin 2 50 thrown over the bolster. Fig. 2 is an end view of the bolster showing the general U-shaped fold 3 and straight sides 4—4 spaced apart sufficiently to snugly fit over the table and to lie flat on each side thereof. 55 By thus setting the bolster in its folded or preformed condition I am enabled to reinforce it with fibrous material such as one or more plies of fabric without losing any of the advantages already mentioned, one ply 60 5 being shown in the drawing, but any number of plies may be used if desirable.

In the manufacture of the bolster the fabric ply (or plies) is preferably embedded in the rubber compound, or other plastic so 65 that it will not be exposed to the injurious

effects of the water and the materials in general that the bolster comes in contact with. The fabric is preferably disposed near the back of the bolster, a thin layer of plastic as for instance the layer 6 serving to protect it while the mass of plastic 7 is disposed at the front of the bolster in order to provide the desired cushion for the skins and hides. The rubber or other plastic may be incorporated with the fibrous component 75 in any desired or well known manner. The sheet after it has been formed is folded about a core or form 8 and placed between the platens 9—9 of a press, and side blocks if desired, the side blocks 10, 11 only being 80 shown which serve to confine the bolster at its top and bottom respectively, the top block being curved to form the curved upper edge of the bolster. The bolster is vulcanized in any desired or preferred manner 85 while in the press, and while but a single bolster has been shown it is obvious that a plurality of bolsters may be shaped and permanently set by vulcanization or otherwise in the press at the same time. 90

A bolster made according to my invention has the advantages, among others, that it will lie flat (without bulges) upon the table, and requires no fastening means, whereby the best results will be attained in 95 the treatment to which the skins or hides are subjected with the least likelihood of injury either to the skins, hides, or bolster. The life of the bolster is thus materially lengthened. The plastic component may be 100 reinforced by one or more plies of strain-resisting material whereby a composite bolster may be formed, the strains to which the bolster is subjected being resisted by the fabric portion thereby leaving the plastic 105 portion free to serve as a cushion for the hides or skins. This permits a rubber or other compound to be selected best suitable for the particular service to which the bolster is intended, and as no reliance need be placed upon the strain-resisting properties of the plastic component it may be as thin and be made of as cheap a compound as the nature of the work to be performed will permit thereby often making a material saving in 110 cost. It will thus be seen that a bolster of the above characteristics is superior, more durable, and can be manufactured at less cost. 115

The folded portion of the bolster has all 120 the characteristics of rubber or other plastic set or vulcanized while in the folded condition, that is to say, it is plainly noticeable that the plastic on both the inside and outside of the fold is in the same condition. There is not the compression on the inside of the fold and the tension on the outside of the fold that is clearly noticeable in a bolster that is folded after vulcanization of the plastic. 125 130

Having thus described my invention what I claim and desire to protect by Letters Patent is:—

1. A bolster for covering both sides of a vertical slab or table used in the treatment of skins and hides comprising a reinforcement of fibrous material and a facing of rubber vulcanized thereto, folded to hang over the top of the slab or table and down both sides thereof the fold being formed to snugly fit the top edge of the slab or table and the sides formed to depend from either side of said fold to normally lay smoothly against the sides of said slab or bolster, to provide a smooth surface about the entire outside of the bolster conforming to the shape of the slab or table, said formation of the fold and positioning of the sides being produced prior to vulcanization to thereby produce permanency of said arrangement of the fold and sides in the finished article.
2. A bolster for covering both sides of a

vertical slab or table used in the treatment of skins and hides comprising a reinforcement of fibrous material and a facing of rubber vulcanized thereto, folded to hang over the top of the slab or table and down both sides thereof the fold being formed to snugly fit the top edge of the slab or table and the sides formed to depend from either side of said fold to normally lay smoothly against the sides of said slab or bolster, to provide a smooth surface about the entire outside of the bolster conforming to the shape of the slab or table, said formation of the fold and positioning of the sides being produced prior to vulcanization to thereby produce permanency of said arrangement of the fold and sides in the finished article.

Signed at Philadelphia in the county of Philadelphia and State of Pennsylvania, 40 this 22nd day of April 1921.

CHESTER E. ALBRIGHT.
